UNITED STATES PATENT OFFICE

2,112,725

SLIDER RETAINING DEVICE

Alfred E. Carlile, Meadville, Pa., assignor to
Talon, Inc., a corporation of Pennsylvania

Application August 12, 1936, Serial No. 95,586

7 Claims. (Cl. 24—205)

My invention relates to slide fasteners, and particularly to means for preventing unintended movement of the slider, resulting in opening up of the fastener.

Various forms of slider locking and retaining devices have been provided, some of which are of simple construction, and very effective in use in the majority of applications of slide fasteners. In some instances, however, for example, in the 10 plackets of dresses, some of these stop devices have caused trouble due to difficulty of releasing the locking device or if a pin lock is used, there are the disadvantages that the pin might tend to catch on the material of the dress and the 15 locking is not dependable due to the fact that sometimes the user will not put the pull in the proper position for locking.

It is an object of my invention to provide a retaining device which will effectively hold the 20 slider in its fully closed position. In such applications as plackets of dresses and especially in corsets and girdles, it is hardly ever desirable to hold the slider at any position except its fully closed position.

It is a further object of my invention to provide a retaining device such that the user will be able to detect positively when the slider is at the limit of its closing position.

It is a still further object of my invention to 30 provide a slider retaining device which will function automatically, which will be simple in construction, and which will never "stick" even when the upper ends of the fastener are bound tightly together.

The manner of accomplishing the objects of 35 my invention and the novel features and functions of the device will readily appear to those skilled in the art in view of the following description of my invention and in the accompanying drawings. In this drawing:

Fig. 1 is a rear plan view of the upper portion of a fastener showing my improved slider retaining device;

Fig. 2 is a cross-sectional view on line 2—2 of 40 Fig. 1; showing the stops in locked position;

Fig. 3 is a detail sectional view showing the parts in locked position; and

Fig. 4 shows only the slider and locking portions of the stop members, the other parts being 45 removed to facilitate illustration of the operation of my improved retaining device.

The fastener illustrated is generally of a conventional type having flexible tape stringers 5, 6, and cooperating rows of spaced fastener elements 50 7 along the adjacent longitudinal edges of the

stringers. The slider also may be of any known type and the one illustrated is generally like one commonly used in the trade. It comprises upper and lower wing portions 8, 9, respectively, connected by a middle portion or neck 10, having a 5 lug 11 to which is connected the pull tab 12. The slider is manipulated by the pull tab along the fastener elements for opening and closing the fastener in a manner which is well understood in the fastener art.

In order to limit the closing movement of the slider, it is necessary to provide stop members and the stop members herein are of a novel form. They each comprise generally a sheet metal fer-rule 13 bent to U-shape around the beaded edge 10 of the stringer. Recesses 14, 15 on opposite sides of the center portion of the slider, and projections 16, 17 on the stop members fitting into and cooperating with these recesses retain the slider in fully closed position. In that position the stop members enter within the slider and the projections automatically enter into the recesses 14 and 15. These recesses are preferably cut out of one or both of the slider wings, herein the lower wing 9, and each of them has an outer wall 18, shown 20 best in Fig. 4, which extends approximately parallel to the longitudinal center line of the fastener or at least they preferably have no inclination diverging outwardly toward the end of the fastener to which the slider is moved in closing the 25 fastener.

In order to urge the stop members outwardly and maintain the projections 16 and 17 in engagement with the outer wall 18 of the recesses, I provide resilient means, herein small rubber pieces 19, 20, which are secured between the stop members and beaded edges of the tapes and project through an opening in the outer wall in each of the stop members. These rubber pieces engage the middle portion or neck 10 of the slider 30 and when the slider is moved over the top stops they will be compressed, the compressive action of the blocks acting to force the stop members outwardly and consequently hold the projections 16 and 17 in engagement with the outer walls of 35 the recesses. It will thus be apparent that in effect the stop members serve as the male element while the recesses on the opposite sides of the slider wing serve as female elements or sockets of snap retaining devices, and when the slider 40 is moved to its topmost or fully closed position, some effort will be required to force the slider completely over the top stops due to the fact that the rubber blocks 19 and 20 must be compressed. 45 In the final movement of the slider the projec- 50 55

tions 16 and 17 will snap into their seats at the bottom of the recesses as will be evident in view of the shape of the recesses illustrated in the drawing:

5 While I have shown and described in this application one embodiment which my invention may assume in practice, it will be understood that this embodiment is merely for the purposes of illustration and that various other forms may be devised within the scope of my invention as defined in the appended claims:

10 What I claim as my invention is:

15 1. In a slide fastener, a pair of stringers having spaced fastener elements along their adjacent edges, a slider movable along said elements for opening and closing the fastener, stop members for limiting the closing movement of said slider, at least a portion of each of the stop members being adapted to enter into the slider, and 20 cooperating means on said stop and an interior wall of the slider for locking the slider in closed position including means for exerting pressure on said stop members laterally and outwardly from the center line of the slider.

25 2. In a slide fastener, the combination of a pair of stringers having fastener elements along their adjacent edges and a slider movable along the elements for opening and closing the fastener, stop members for limiting closing movement of the slider, said stop members being of a size and shape to enter the slider when it is moved to fully closed position, said slider having recesses intermediate the sides thereof, projections on said stop members adapted to enter into 30 said recesses for retaining the slider in closed position, and yielding means for pressing said stop members outwardly to hold said projections in

engagement with the outer walls of the recesses.

3. The combination defined in claim 2 where-
in said recesses have outer walls substantially parallel with the longitudinal center line of the fastener, and yielding means for holding said 5 stop members in position to maintain said pro-
jections against said outer walls.

4. The combination defined in claim 2 where-
in the yielding means is carried by the stop mem-
bers.

10 5. The combination defined in claim 2 where-
in the yielding means consists of pieces of re-
silient rubber mounted on the outer edges of the 15 stop members and adapted to bear against the central portion of the slider to urge the stop mem-
bers outwardly to maintain the projections in engagement with the recesses.

6. The combination defined in claim 2 where-
in the shoulder on the stop member consists of 20 a cylindrical surface.

25 7. In a slide fastener the combination of a pair of stringers disposed in a common plane and having spaced fastener elements along their ad-
jacent edges, a slider including a plate parallel to said plane and movable along the elements for opening and closing the fastener, the slider having formed in the inner face of the plate a recess having an outer wall substantially perpendicular to the plane of the stringers and substantially parallel to the longitudinal center line of the 30 fastener, a stop member for limiting closing movement of the slider, and a shoulder on the stop member adapted to enter said recess and engage said outer wall to prevent opening move-
ment of the slider under a force tending to sepa- 35 rate the stringers.

ALFRED E. CARLILE.
